[57] CLAIM

The ornamental design for a combined hoe and rake head assembly, as shown and described.

DESCRIPTION

FIG. 1 is a top and rear perspective view of a combined hoe and rake head assembly showing a first embodiment of my new design;

FIG. 2 is an exploded front and top perspective view thereof;

FIG. 3 is a side elevational view thereof, the side opposite being a mirror image;

FIG. 4 is a top and rear perspective view of a second embodiment thereof, the only difference residing in the width of the rake element; and

FIG. 5 is a top and rear perspective view of a third embodiment thereof, the only difference residing in the width of the rake and hoe elements.

The broken-line showing of a portion of the handle is for illustrative purposes only and forms no part of the claimed design.
